(57) **CLAIM**

The ornamental design for a foldable storage rack, as shown and described.

DESCRIPTION

FIG. 1 is a perspective view of a foldable storage rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the foldable storage rack taken from the circle portion in FIG. 1; and,

FIG. 9 is another enlarged view of the foldable storage rack taken from the circle portion in FIG. 1.
